Primary Examiner — Leanne Was-Englehart*Assistant Examiner* — Yelizaveta Y Masalimova(74) *Attorney, Agent, or Firm* — Marshall A. Lerner; Steven J. Kim; Kleinberg & Lerner, LLP(57) **CLAIM**

The ornamental design for a midsole periphery as shown and described.

DESCRIPTION

FIG. 1 is a front perspective view of a midsole periphery in accordance with my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dash-dash broken lines shown in the drawings represent the upper and parts of the shoe that form no part of the claimed design. The grayed halftone portions shown in a perimeter of dash-dash broken lines form no part of the claimed design.
